(57) **CLAIM**

The ornamental design for an electric teapot, as shown and described.

DESCRIPTION

FIG. 1 is a perspective view of an embodiment of an electric teapot showing my new design.

FIG. 2 is a front elevational view of the electric teapot of FIG. 1.

FIG. 3 is a rear elevational view of the electric teapot of FIG. 1.

FIG. 4 is a right side elevational view of the electric teapot of FIG. 1.

FIG. 5 is a left side elevational view of the electric teapot of FIG. 1.

FIG. 6 is a top plan view of the electric teapot of FIG. 1; and, FIG. 7 is a bottom plan view of the electric teapot of FIG. 1. The broken lines appearing in the figures are for the purpose of illustrating the environmental structure of the article of the claimed design and form no part of the claimed design.
